UNITED STATES PATENT OFFICE.

WILLIAM MEYER, OF CHICAGO, ILLINOIS.

X-RAY APPARATUS.

Application filed March 9, 1922. Serial No. 542,211.

My invention relates to X-ray apparatus and the like and is especially directed to X-ray apparatus of that type in which a grid or so-called "Bucky" diaphragm is employed for screening out or eliminating cross rays before they reach the radiographic plate or film, particularly such cross or secondary rays as are set up in and emerge from the body of the patient.

It is well known in the art that where these secondary rays, are not diaphragmed or screened out an objectionable "fog" or "clouding" is produced and the diagnostic value of the radiograph is decreased. The matter of eliminating secondary radiation from the body, to secure clear, sharp detail is particularly important where the individual or patient is heavy or especially corpulent. It has become the practice to screen out secondary or cross rays by moving a grid or grating made up of alternate laminations of wood or other material penetrable by X-rays and laminations of material impermeable by such rays, across the rays emanating from the source of X-rays employed between the patient and the plate or film. I find that the grid mechanisms provided heretofore for use in this connection have either not possessed sufficient structural strength or have not permitted that ready penetration of the direct rays which is so essential.

It is an object of my invention to provide a simple, strong, durable and efficient grid through which even the softest rays will readily penetrate without obstruction.

Another object of my invention is the provision of a simple, inexpensive, efficient and effective process of making the same.

A further object of my invention is the provision of a grid operating and controlling mechanism the functioning and structure of which will be an improvement over the functioning and structures of the prior art mechanisms.

A still further object is to improve the functioning and structure of the various parts of the entire apparatus and to improve the assembly and relation therebetween.

The invention will be more readily understood by reference to the accompanying drawings, in which I have illustrated a particular embodiment in order to fully apprise those skilled in the art how to construct and practice the same.

In the drawings:

Figure 1 is a perspective view of an X-ray table embodying my invention;

Fig. 2 is a top plan view partially in section of the "Bucky" diaphragm;

Fig. 3 is a side elevational view of the same;

Fig. 4 is a vertical transverse section taken substantially on the line 4—4 of Figure 2;

Figs. 5 and 6 are fragmentary isometric views of the strips or laminations from which the grid is made up;

Fig. 7 is an isometric view of these strips with the first step of the process performed;

Fig. 8 is a similar view after the next step of the process has been performed;

Fig. 9 is an enlarged fragmentary section taken on the line 9—9 of Fig. 2;

Figure 10 is a vertical section taken on the line 10—10 of Fig. 9;

Fig. 11 is an enlarged fragmentary side elevational view of the diaphragm frame showing the releasing arrangement provided for the grid operating mechanism;

Fig. 12 is an axial sectional view through the dash pot mechanism for controlling the movement of the grid;

Fig. 13 is a transverse vertical section taken on the line 13—13 of Figure 12;

Fig. 14 is an enlarged fragmentary perspective view showing the pawl and ratchet device for holding the binding band;

Fig. 15 is an enlarged fragmentary perspective view showing an alternative connection between the overhead conductors and the take-up reels employed;

Fig. 16 is an enlarged fragmentary cross section through the structure of the grid; and

Fig. 17 is a fragmentary elevational view of the tube standard showing an alternative balancing arrangement for the carriage mounted thereupon.

In the embodiment of the invention selected for illustration, the table 1 comprises a pair of corner posts or legs 2 at one end and a pair of relatively shorter legs or posts 2' at the opposite end secured together by side pieces 3 and end pieces 4, to form a rectangular frame. A rail 5 extends between and is secured at its opposite ends to one pair of posts or legs 2—2' adjacent their lower ends. A pair of bracing rods 6 and 7 secured at a common point to the rail 5, extend up and are secured at their opposite ends.

ends to the respective side pieces of the table. The sides and ends of the table may be otherwise braced by suitable transverse and diagonal corner braces as desired.

5 A top portion 8 extends over and is secured to that end of the table adjacent the legs 2-2. A top portion 9 set down from the top portion 8 to receive the so-called "Bucky" diaphragm mechanism 10 which 10 will be more fully described as this description proceeds, extends over and is secured to the opposite end of the table frame. The top portions 8 and 9 are preferably finished in natural wood as is the rest of the table, 15 although it is to be understood that the top portion 8 may, for example, be covered with suitable fabric or the like if so desired. A foot board 11 hinged at the outer end of the top portion 8 is finished in a similar manner 20 and adapted to be dropped down and retained in any desired position by a quadrant 12 adapted for cooperation with a pin, for example, projecting from the adjacent leg 2.

The four corner posts or legs 2-2 and 25 2'-2' are provided with anti-friction rollers or casters 13 in order that the table may be readily moved to any desired position. One pair of legs is further provided with suitable stops 14, by means of which the table 30 may be locked against accidental movement.

A tube standard 15 is supported and guided longitudinally along one side of the table by guide rods 16 secured along the upper edge of the rail 5 and the lower edge 35 of the adjacent side piece 3. Guide members 17 bearing rollers 18 cooperable with the rods 16 are clamped or otherwise secured in proper position upon the standard 15. The radiographic or X-ray tube 19, is 40 enclosed in a lead glass shield 20, supported by an arm 21 angularly adjustable about the end of an extension arm 22. The arm 22 is adjustably mounted in a frame or carriage member 23 which is in turn mounted upon 45 the standard 15 for vertical and angular adjustment thereupon. The tube shown is of the well known Coolidge type having the usual high potential conductor 24 connected to the anode thereof at one end and a high 50 potential conductor 25 and cathode heating conductor 26 connected to the other end. The drop leads 24, 25 and 26 especially the leads 25, 26 in the cathode heating circuit are preferably insulated to maintain constant resistances in the circuits. These leads 55 24, 25 and 26 unwind from spring take-up reels 27 depending from a transversely arranged cross arm 28, which arm is supported at one end by a mounting piece 29 secured 60 to the cap 30 closing the top of the tubular standard 15. The arm 28 is of wood or otherwise insulated. The cable 31 attached at one end to the frame or carriage member 23 may extend up and over a pulley and be 65 attached at its opposite end to a counter-

weight movable within the standard 15 as shown in Fig. 1 or it may extend up and over a pulley 190 down to form a bight 192, up over a pulley 193 and down and connected at its opposite end to the carriage 23 as 70 shown in Fig. 17. In the latter case the counterweight 194 is mounted as through a suitable hook or eye 195 in the bight 192 of the cable.

The high potential and heating currents 75 are conducted from suitable sources (not shown) to hollow conducting rods or tubes 32 extending longitudinally over the table and secured at their opposite ends in transversely arranged carrying pieces 33, each 80 of which is secured at one end to the upper end of an upright post 34. Suitable binding posts 32' for attaching the high potential conductors are secured to the ends of the tubes or hollow rods 32 and they serve the 85 additional function of anchoring the ends of the rods to the wooden cross frame pieces 33. The lower ends of the posts 34 are secured to one side of the table adjacent its opposite ends. Electrical connection between the 90 conductors 24, 25 and 26 and the respective conducting rods 32 is had through contact pieces 35 engaging the rods 32 at one end and secured at their opposite ends to the cross arm 28 and electrically connected with the 95 respective conductors 24, 25 and 26 in the manner shown in Figs. 1 or 15. A radiator 38 provides for dissipating or radiating the heat away from the tube 19.

The rays emanating from the tube 19 penetrate 100 the desired portion of the patient's body and produce the desired shadow graph by acting upon a sensitized plate or film contained in a holder 39 movable over the top portion 9. The plate or film is preferably 105 arranged in a cassette of the type disclosed in my co-pending application, Serial No. 542,212, filed March 9, 1922, which is then arranged in the holder 39, which is provided with a retention spring 40 for preventing 110 displacement thereof. The under surface of the holder 39 is provided with a pair of guide rollers 41 which engage in a guide slot 42 extending longitudinally through the top portion 9.

The "Bucky" diaphragm mechanism comprises a frame made of metallic side pieces 45 and end pieces 46 secured together and mounted upon the table top portion 9. The upper edges of the end pieces 46 are formed 120 with concave edges and the side pieces 45 are provided with flanges 47 extending inwardly along the curvature of these edges.

A novel patent supporting surface or diaphragm covering 50 transparent to X-rays is arranged over and secured to the upper concave edges of the end pieces 46 and to the inwardly extending flanges 47. This surface or covering 50 is made up of "bakelite" or other equivalent suitable material 125 130

such as that more fully disclosed and claimed in my co-pending application, Serial No. 542,210, filed March 9, 1922, consisting of a compacted web or felting of vegetable fiber, more specifically characterized as a non-metallic, isotropic material not subject to deterioration by X-rays, a stiff non-hygrosopic material having sufficient structural strength, no grain and better permeability, one that will not shrink, warp or bend and one having such a heat conductivity that it will be more pleasing to the body of the patient and not chilling as is the case where an aluminum or other metallic surface is employed.

The grid 51 mounted in the diaphragm frame for movement across the X-rays is made up of alternate laminae of material readily penetrable by X-rays such as wood or the like and material non-penetrable by X-rays such as lead foil, or a composition of lead foil and antimony. The wood laminae are in the form of strips 60 having longitudinal tongues 61 extending along one surface from end to end. By the first step in the process of making up the grid, a lead foil strip or lamina 62 is secured, preferably with silicate of soda or water glass, upon the opposite or uninterrupted surfaces of each of the strips 60. The surfaces thus faced are then grooved longitudinally as shown at 64 in Fig. 8 to receive the longitudinal tongues 61 of the adjacent wood strips and the strips or laminae are then mounted or secured in a frame comprising end pieces 65 and 66 and channeled side pieces 67 suitably secured together. The side pieces may be bowed inwardly and the ends thereof sprung in and secured to the end pieces to firmly clamp or bind the grid structure together.

The grid structure is curved as shown for the usual purpose, i. e., so that a maximum number of laminations will lie substantially radially with respect to the source of rays throughout its various positions with respect to the grid. To secure the desired curvature, the wood strips 60 and even the strips 62 may be made wedge shaped or the clamping together of parallel faced strips may be sufficient to give the desired curvature. As the grid is moved across the rays projected from the tube 19 as will be presently described, the rays directly from the source will pass through the strips 60 while any non-radial or cross rays and particularly such secondary rays as are set up in and emerge from the body of the patient will be screened out or eliminated by the non-penetrable strips or laminae 62. The grid or diaphragm thus formed is mechanically strong being secured by the tongue and groove against shifting or offsetting.

One end of a cord or cable 68 is secured 65 together with the free end of a metallic band

or tape 69 to the under surface of the end piece 65 substantially centrally as by means of a suitable bolt as shown. The opposite end of the cable 68 is secured together with the free end of a metallic band or tape 70 to the under surface of the end piece 66 in a similar manner. The cable 68 extends over sheaves 71 out along the outer surface of the adjacent side piece 45 and is looped intermediate its ends through notches 72 in the outer disk of a sheave-like member 74 fixedly mounted upon a shaft 75.

The outer end of the shaft 75 is provided with a handle 76. The inner end of the shaft extends through the adjacent frame piece 45 and into the cylinder of a dash pot 78, (Fig. 12). A pinion 79 secured to the end of the shaft meshes with a rack 80 to the opposite ends of which are secured plunger heads or pistons 81 and 82 respectively, operable as a unit with the rack 80 within the cylinder 78. A port 83 through the piston 81 places that portion of the interior of the cylinder 78 between the pistons 81 and 82 in communication with that portion of the cylinder to the left of the piston 81 (Fig. 12) at all times. A port 84 through the piston 82 provides for communication between the interior of the cylinder 78 between the pistons 81 and 82 and that portion to the right of the piston 82 (Fig. 12) at such times as will hereinafter appear. This latter port 84 is controlled by a ball valve member 85 arranged to seat upon a cooperating seat in the outer face of the piston 82 to close the port 84 upon movement of the piston and rack device to the right, (Fig. 12). The valve member 85 is held in place by a valve cage 86 attached to the piston 82.

A passageway 90 formed in the cylinder casting 78 and closed at its outer end communicates at its inner end with the interior of the enlarged integral boss 91 within which the pinion 79 is arranged and thereby with the interior of the cylinder 78 between the pistons 81 and 82. A passage 92 which may be in the nature of a drill hole suitably plugged at its outer end provides communication between the interior of the cylinder 78 to the right of the piston 82 and the passage 90 by way of a connecting passage 94 formed in the cylinder casting as shown in Figure 13. A needle valve 95 having its stem threaded through a valve bushing 96 which in turn is threaded into the casting 78 is provided at its outer end with a knurled knob 97 by means of which the valve may be adjusted to control the communication between the interior of the cylinder 78 to the right of the piston 82 and the by-pass back to the interior of the cylinder between the pistons 81 and 82. The cylinder 78 is filled with a suitable fluid, preferably a viscous liquid such as a suit-

able oil the rate of flow of which from that portion of the cylinder beyond the piston 82 back to the central portion, governs the movement of the plunger and rack member 5 to the right, the ball valve 85 being firmly seated by such movement to close the port 84. This by-passing or flow back to the central portion of the cylinder may be adjusted or regulated by the needle valve 95 10 to regulate the rate of movement of the pistons and rack.

The bands or tapes 69 and 70 unwind from and wind upon reels 100 and 101 loosely mounted upon a shaft 102 arranged 15 longitudinally of the "Bucky" diaphragm frame adjacent one of the sides thereof and journaled at its ends in bearings 103 (Fig. 9) carried by the end pieces 46. A helical take-up spring 104 coiled about one end of 20 the shaft 101 and secured at one end to the reel 100 is secured at its opposite end to a collar 105 fixed upon the shaft 101. A similar take-up spring 106 coiled about the opposite end of the shaft 101 is secured at one 25 end to the reel 102 and at its opposite end to a collar 107 fixed upon the shaft 101. A worm 108 mounted in bearing lugs projecting from the end piece 46 with a worm wheel 109 fixed upon the adjacent end of 30 the shaft 102 holds the shaft 102 against rotation. The outer end of the worm 108 is provided with a slot 110 for engagement by a suitable tool 111 as shown in Figure 2 35 for the purpose of rotating the shaft and thereby adjusting the tension of the springs 104 and 106 as desired. This provision for 40 adjusting the springs 104 and 106 provides with the adjustable dash pot arrangement already described, a great range of regulation 45 for the speed of movement of the grid 51. Anti-friction rollers 170 carried by the end pieces of the grid frame are mounted to travel upon tracks 171 carried by the opposite end walls 46.

45 From the foregoing description it will now be apparent that when the sheave member 74 is turned in a counterclockwise direction (Fig. 3) the grid 51 is moved from the full line position shown in Fig. 4 to the 50 dotted line position. At the same time the bands 69 and 70 are unwound from their respective reels and the springs 104 and 106 wound or tensioned. As the sheave member 74 nears the end of its angular movement a 55 lug 115 extending from the inner surface thereof, engages a pawl 116 carried by a lever 117 which pawl projects outwardly through an opening 118 in the side frame 45, swinging the pawl 116 aside and continuing into engagement with a stop 119 projecting from the outer face of the frame piece. The lever 117 is pivoted at 120 to the inner face of the frame piece 45 and is 60 engaged by a suitable spring 121 so that upon movement of the lug 115 past the

pawl 116 and into engagement with the stop 119 the lever will be returned by the spring 121 to the position shown in Figure 11, the pawl 116 engaging over the lug 115 and thereby preventing retrograde movement or 70 rotation of the sheave member 74.

Cords or cables 125 and 126 attached to the opposite ends of the pivoted lever and extending out from the opposite ends of the diaphragm mechanism are provided for releasing the pawl 116. These cables are 75 shown in Fig. 1 as broken off.

By pulling either of the cords 125 or 126 the lever 117 is swung about its pivot 120 against the tension of the spring 121 and 80 the pawl 116 carried thereby is moved out of engagement with the lug 115 permitting the tensioned springs 104 and 106 to wind the bands 69 and 70 back upon the reels 100 and 101 and thereby move the grid 51 at a 85 suitable speed governed by the needle valve 95 of the dash pot mechanism 78 and the tension of the spring 104-106, back into the full line position shown in Figure 4. As the grid 51 nears the end of its movement in 90 this direction the lug 115 engages a spring pressed hammer arm 130 and swings the same outwardly against the tension of a spring 131. Upon being released the hammer 130 is swung by the spring 131 into engagement with a bell 132 to indicate that the grid is nearing the end of its movement. Upon movement of the lug 115 into engagement with a stop 133 the grid is brought to 95 rest.

A fabric band 140 attached to a bar 141 extending along the upper edge of one side of the diaphragm frame provides for compressing and holding in place the particular part of the body of the patient to be examined. The free end of the band 140 carries a border rod or frame piece 142 insertible into a longitudinal slot 143 in a tubular drum member 144 mounted for rotation in lugs 145 extending from the opposite side 110 of the diaphragm frame. A stud 146 projecting from one end of the tubular winding member 144 carries a handle 147 for turning the tube and a ratchet 148 cooperable with a pawl 149 pivoted to the adjacent 115 lug 145 for holding the winding member in the position at which the handle 147 is released upon winding the free end of the band 140 upon the winding member to bind the patient in place.

The operating sheave 74, cord 68, bell 132 and sheave 71 are enclosed by a cover 150 shown in place in Fig. 1. The outer end 46 of the diaphragm frame is provided with a notch 151 to permit movement of the holder 125 39 at least partially therethrough, the adjacent end piece 4 of the table being notched at 152 to permit the accompanying movement of the retention spring 40 out through the end of the table. A notch 153 in the top 120

portion 9 permits convenient access to the holder and cassette arranged therein.

The holder 39 is provided with an arm 160 which arm extends out through a longitudinal opening 161 in the side piece 45 of the diaphragm frame into the path of movement of the standard 15 along the table. This arm is preferably positioned on the carrier 39 so that upon engagement with the standard 15 as shown in Figure 2, the tube or source 19 carried thereby will be positioned substantially centrally with respect to the sensitized plate or film arranged within the holder 39. A pointer 162 carried by the standard 15 is adapted for cooperation with a scale along the adjacent side of the diaphragm frame to indicate the position of the standard along the diaphragm mechanism and thereby facilitate the positioning of the standard. Adjacent its outer end the arm 160 carries a visualizing bar 163 the length and position longitudinally along the table of which is substantially that of the sensitized plate or film so that the position of the plate or film may be quickly visualized from the side of the table.

While the various details and the arrangements shown are now considered preferable, it is to be understood that such details and arrangements may be varied within the scope of my invention.

I claim:

1. In a diaphragm of the class described, the combination of a grid and a covering for said grid, said covering comprising a relatively thin sheet composed of a phenol product of condensation.

2. In combination, a "Bucky" diaphragm, a tube standard movable therealong, a plate holder adjustable therebeneath, said holder having an arm extending into the path of movement of the tube standard.

3. In combination, a "Bucky" diaphragm, a tube standard movable therealong, a plate holder adjustable therebeneath, said holder having an extending arm and means carried by said arm for visualizing the position of the plate or film from the side of the table.

4. In a device of the class described, a movable grid, a flexible element having connection with said grid adjacent its opposite ends, and means cooperable with said flexible element between its points of connection with the grid for actuating or moving the grid.

5. In a device of the class described, a movable grid, a flexible element having connection with said grid adjacent its opposite ends, a rotatable winding member, the flexible element being looped about said winding member to actuate the grid by rotation thereof.

6. In a device of the class described, a movable grid, a flexible element connected with said grid and adapted for winding

upon and unwinding from a take-up reel, spring means for opposing unwinding of said flexible element, means for moving the grid in one direction, said spring means moving the grid in the opposite direction. 70

7. In a device of the class described, a movable grid, a flexible element connected with said grid and adapted for winding upon and unwinding from a take-up reel mounted upon a shaft, a helical spring coiled 75 about said shaft and connected to the shaft and said reel, and means for rotating the shaft to adjust the tension of said spring.

8. In a device of the class described, a movable grid, flexible elements connected with said grid and adapted for winding upon and unwinding from take-up reels mounted upon a common shaft, a worm wheel on said shaft, a worm cooperating with said worm wheel, said worm being adapted for rotation to turn the shaft and adjust the tension of said spring. 80

9. In combination, a diaphragm frame, a grid movable therein, a flexible element, a pair of bands, said bands being connected to the grid with the opposite ends of said continuous flexible element and adapted for winding upon and unwinding from take-up reels mounted upon a common shaft arranged through the diaphragm frame, means 90 cooperable with the flexible element within its length for moving the grid in one direction and spring means opposing movement of said grid by said first means, said spring means being adapted for moving the grid 95 in the opposite direction.

10. In combination, a movable grid, means for moving said grid, stop means for preventing movement of the grid and remote controlled means for releasing said stop means to permit movement of the grid. 105

11. In combination, a movable grid, a cable connected at its opposite ends to said grid, a winding member, the cable being looped about said member to actuate the grid by rotation thereof, spring means wound upon movement of the grid by rotation of said member, said spring means being adapted for moving the grid in the opposite direction, means for preventing movement of the grid by said spring means, and means for releasing said last means to permit movement of the grid by said spring means. 110

12. In combination, a movable grid, a rotatable member for moving said grid, a dash pot for regulating the movement of the grid, said dash pot being connected with said rotatable member through a rack and pinion engagement therebetween. 120

13. In combination, a movable grid, a rotatable member for moving said grid, a dash pot operable through a pinion and cooperating rack for regulating the movement of the grid, and means for regulating said dash pot and thereby the movement of the grid. 125

14. In an X-ray table, a supporting frame having a top portion adjacent one end, a top portion adjacent the opposite end, said second top portion being offset down from said first top portion, and a diaphragm mechanism supported by said downwardly offset top portion in substantially the plane of said first top portion.
15. In combination, a tube standard, a carriage mounted for movement thereupon, a cable connected at its opposite ends to said carriage and a weight arranged in a bight in said cable and slideable in said standard.
16. In combination, a tube standard, a carriage mounted for movement thereupon, a cable connected at one end to said carriage, said cable extending up over a pulley, down to form a bight up over a second pulley and down and connected at its opposite end to the carriage, and a weight arranged in the bight in said cable.
17. In combination, a movable grid, means for moving said grid, stop means for preventing movement of the grid, and means for releasing said stop means to permit movement of the grid.
18. In combination, a movable grid, spring means for moving said grid in one direction, and means for moving said grid in the other direction, said second means tensioning said spring means.
19. In combination, a movable grid, means for moving said grid and dash pot means for controlling the movement of the grid.
20. In a device of the class described, a movable grid, a flexible element connected therewith, and means connected with said flexible element for moving the grid therethrough.
21. In a device of the class described, a movable grid, a flexible element connected therewith, and means connected with said flexible element for moving the grid in opposite directions, said means including a spring take-up reel and a winding element.

In witness whereof, I hereunto subscribe my name this 6th day of March, 1922.

WILLIAM MEYER.
